UNITED STATES PATENT OFFICE

ALFRED BONNEY, JR., OF VERONA, NEW JERSEY, ASSIGNOR TO WESTINGHOUSE LAMP COMPANY, A CORPORATION OF PENNSYLVANIA

DESIGN FOR AN INCANDESCENT ELECTRIC LAMP BULB

Application filed January 20, 1931. Serial No. 38,399. Term of patent 3½ years.

To all whom it may concern:

Be it known that I, ALFRED BONNEY, JR., a citizen of the United States, residing in Verona, in the county of Essex and State of New Jersey, have invented a new, original, and ornamental Design for an Incandescent Electric Lamp Bulb, of which the following is a specification, reference being had to the accompanying drawings, forming part thereof.

Fig. 1 is a side elevational view of an incandescent lamp bulb embodying the present ornamental design.

Fig. 2 is a top or plan view of the bulb shown in Fig. 1.

The essential feature of the design is that it is suggestive of a bell, although not proportioned as such; the lower dome-shaped end of the design merging into the lower edge of the outer wall.

I claim:—

The ornamental design for an incandescent electric lamp bulb, as shown and described.

ALFRED BONNEY, JR.
